Fred Hayn

ATTORNEY.

UNITED STATES PATENT OFFICE.

HERBERT C. HAMER, OF CLOVIS, CALIFORNIA, ASSIGNOR OF ONE-HALF TO WARREN E. SADLER, OF SANTA ANA, CALIFORNIA.

NAIL STRIPPER.

Application filed March 17, 1924. Serial No. 699,725.

My invention relates to a new and improved form of nail stripper in which the nails automatically align themselves so that they may be withdrawn with their heads ⁵ up.

It is an object of my invention to provide an improved nail stripper in which it will be impossible for the nails to become clogged or retarded, thereby preventing ¹⁰ them from being easily and quickly withdrawn from said nail stripper at the point of delivery.

It is a further object of my invention to provide a nail chute composed of triangular ¹⁵ sections adapted to be spaced apart to form troughs, the inclined sides of said sections leading to the slots formed by spacing said sections apart, rods being secured to said sections, which rods are adapted to provide nail tracks for positioning the nails ²⁰ with their heads upward.

It is a further object of my invention to provide a series of nail guides between ²⁵ which the nail tracks are adapted to project, whereby the nails are prevented from becoming clogged in their progress to the point of delivery, and thus obviate any retardation thereof in their forward movement.

³⁰ A further object of my invention is to provide said nail guides with nail deflecting portions, whereby the delivery of the nails from said nail tracks to said nail guides is facilitated.

³⁵ It is also an object of my invention to provide a means for adjusting the width, both of said nail tracks, and said nail guides, whereby both may accommodate nails of different sizes.

⁴⁰ It is also an object of my invention to provide a strap with adjusting means extending across the nail chute, whereby the spaces between said sections may be adjusted, said strap being also provided with a means extending through at least one of ⁴⁵ said sections, whereby said sections may be secured in position.

It is also an object of my invention to provide a means for adjusting the height ⁵⁰ of said nail chute and said hopper, and also a means for adjusting the height of said nail guides and said nail tracks.

It is also an object of my invention to provide a means whereby it is possible to

collapse my nail stripper, and house the ⁵⁵ same in a box.

It is also an object of my invention to provide a nail stripper made up of a minimum number of parts, which nail stripper is inexpensive and easy to manufacture, and ⁶⁰ which is thoroughly practical and efficient in operation.

Further objects and advantages of my device will become apparent as the description ⁶⁵ thereof proceeds.

Reference is had to the accompanying drawings, in which similar reference characters indicate corresponding parts in all the figures, and in which—

Fig. 1 is a side elevation of my device ⁷⁰ showing the same as ready for operation,

Fig. 2 is an end elevation of Fig. 1, looking from the right,

Fig. 3 is an end elevation of Fig. 1, looking from the left, the cover being shown ⁷⁵ broken away to disclose the construction,

Fig. 4 is a view in side elevation, similar to Fig. 1, but showing the opposite side thereof,

Fig. 5 is an enlarged, diagrammatic view ⁸⁰ of one end of the nail chute, showing the triangular sections, and the strap for adjusting the spaces between said sections, and

Fig. 6 is a fragmentary perspective view ⁸⁵ of the cross-bars for adjusting the width of the nail guides.

In detail, the box 2 is provided with a cover 1 hinged thereto by means of the hinges 25. Secured to the cover 1 by means of the wing nut and bolt 32, is a hopper 3, ⁹⁰ preferably shown inclined, as disclosed in Figs. 1 and 4. A nail chute 4, pivotally connected with the hopper 3 by means of flanges 28, is adapted to be held in position by a standard 6, adjustably secured to the ⁹⁵ box 2, by means of the wing nut and bolt 23. This standard is offset as shown in Figs. 2 and 3 to permit the nail stripper to be collapsed and housed in the box 2. Holes 33 and the wing nut and bolt 34, ¹⁰⁰ permit the height of both hopper and nail chute to be adjusted by the standard 6.

The nail chute 4, as shown more clearly in Fig. 5, is made up of a series of triangular sections 16, 17, and 18, the two outermost sections being substantially in the shape of right angled triangles, while the inner section is in the shape of an isosceles

triangle. Said sections are spaced apart as shown, and rods 5 are mounted on said sections to provide nail tracks, whereby the nails may be positioned in said chute with 5 their heads upward. One end of said nail chute is closed by means of the plate 35.

To adjust the width of the tracks 5 a strap is provided, preferably, though not necessarily, made up of sections 14 and 15, 10 secured together in any desirable manner, such, for example, as by soldering. Said sections are adjusted by means of the wing nuts 22, threaded on to the sections 15, as shown in Fig. 5. To hold the sections 16, 15 17, and 18 in position, a bolt 19, extending through the section 17, is provided, and the wing nut 21, and the nut or washer 20, provide a means for adjustably securing said sections in position, as will be clear.

20 The nail tracks 5 project beyond the nail chute, and are adapted to extend between each pair of companion nail guides 12. The ends 11 of said nail guides are bent outwardly, as clearly shown in Figs. 2 and 3. 25 These ends 11 form nail deflecting portions for preventing the clogging of the nails in their downward movement to the point of delivery. Said nail deflecting portions are adapted to be secured to the nail chute, as 30 shown in Figs. 1, 2, 3, and 4.

To provide a means for adjusting the width of the nail guides 12, cross-bars 10 and 27 are provided, shown more clearly in Figs. 3 and 6, a wing nut and bolt 26 being 35 used to hold them firmly in position. One end of each pair of the nail guides is secured to the bar 27, and is adapted to move in a slot 31, shown in Fig. 6; the other end of each pair is secured to the cross-bar 10, 40 the bolt of the wing nut 26 moving in a slot, as will be obvious.

Side bars 13, as shown more clearly in Figs. 2 and 3, connect the bar 27 to the chute 4. To adjust the cross-bars 10 and 45 27 vertically, and thus raise or lower the nail guides 12 and the chute 4, supporting arms 7 and 8, provided with wing nut and bolts 24, are provided, one of said arms, in this instance as the arm 7, being offset, 50 to afford a means whereby the stripper may be collapsed so that it may be housed in the box 2. The bar 27 is pivoted to the arms 7 and 8 by means of the pivots 30.

The box 2 is provided with a suitable handle 9 and locking means L for holding the cover 1 in position when the nail stripper is collapsed.

In operation, the nails N are placed in the hopper 3 and if desired sprinkled with 60 powdered soap-stone, and fall by gravity. The percussion caused by the hammering of the workmen will cause the nails to slide from the hopper 3 into the chute 4. In rolling upon the inclined walls of the sections 65 of the chute, the nails will fall into the

slots between the nail tracks 5, and will be held by their heads, and gradually work themselves down onto the nail guides 12. Due to the nail deflecting portions 11, and the fact that the nail tracks 5 extend between the nail guides 12, said nails are prevented from clogging, or being retarded, as is caused by the nail strippers now in common use. The nails on the guides 12 may be grasped quickly with their heads 75 up, by handfuls, and are thus in position ready to be driven.

It is, of course, understood that my device in practice may be modified through a wide range, and I do not therefore propose to be 80 limited to the exact construction shown and described.

I claim as my invention:

1. In a nail stripper, a box, a cover hinged thereto, a hopper secured to said cover and adapted to extend over said box, a chute pivotally secured to said hopper, a single standard adapted to support said chute and said hopper, said standard being provided with means whereby the height of said chute may be adjusted, one or more sets of nail guides secured at one end to said chute, a pair of cross-bars for securing the other ends of said nail guides, means on said cross-bars for adjusting the distance between said nail guides, a pair of supporting arms for supporting said cross-bars, and means on said arms for adjusting the height of said cross-bars and said nail guides, substantially as 95 described.

2. In a nail stripper, a box, a cover hinged thereto, a hopper secured to said cover and adapted to extend over said box, a chute pivotally secured to said hopper, means for supporting said chute, said means being provided with devices whereby said means may be adjusted, one or more sets of nail tracks mounted in said chute, one or more sets of nail guides adapted to support said chute at one end, a pair of cross-bars for 110 supporting the other ends of said nail guides, said nail tracks being adapted to extend between said nail guides, and adjustable means for supporting said cross-bars, adapted to adjust the height of said cross-bars and said nail guides.

3. In a nail stripper, a box, a cover hinged thereto, a hopper secured to said cover and adapted to extend over said box, a chute secured to said hopper, a standard for supporting said chute, means on said standard for adjusting the height of said chute, nail tracks mounted on said chute, nail guides supporting the other end of said chute, a pair of cross-bars secured to and supporting said nail guides, said nail tracks being adapted to project between said nail guides, said nail guides being provided with nail deflecting portions for insuring that the nails are not clogged and thus re- 125 130

tarded in their movement, and adjustable means for supporting said cross-bars, said last mentioned means being adapted to adjust the height of said cross-bars, said nail guides and said chute.

4. In a nail stripper, an inclined receptacle for housing nails, a nail chute secured to said receptacle, means carried by said chute for positioning the nails with their heads upward, and nail guiding means leading from said chute and between which said first mentioned means are adapted to project whereby said nails may be prevented from clogging, at the same time permitting them to be withdrawn, substantially as described.

5. In a nail stripper, a nail chute comprising a set of outer and inner sections adapted to form troughs, triangular in cross-section, said sections being spaced apart, wire rods associated with said sections, and projecting above the base portions of said sections, for positioning the nails with their heads upward and to facilitate their free and unobstructed movement, a set of nail guides between which said wire rods extend, and flared nail deflecting portions associated with said rods to prevent said nails from clogging.

6. In a nail stripper, a hopper for housing nails, a nail chute connected to said hopper, nail tracks mounted in said chute, nail guides leading from said chute, and between which said nail tracks are adapted to extend, means on said chute for adjusting the width of said nail tracks, means for adjusting the width of said nail guides, and means for adjusting the height of said nail guides, substantially as described.

7. In a nail stripper, an inclined hopper for housing nails, a nail chute connected with said hopper, nail tracks mounted in said chute, nail guides leading from said

chute, said nail tracks being adapted to project between said nail guides, said nail guides being provided with means for preventing the retardation of the nails, means for adjusting the width of said nail tracks, and means for adjusting the width of said nail guides, substantially as described.

8. In a nail stripper, a hopper for housing nails, a nail chute connected with said hopper, means on said chute for positioning the nails with their heads upward, means for guiding said nails to the point of delivery, said first mentioned means being adapted to project between said second mentioned means, said second mentioned means being provided with means for preventing the retardation of the nails, means for adjusting said first mentioned means to accommodate different sizes of nails, means for adjusting the width of said second mentioned means also for accommodating different sizes of nails, and means for connecting said last mentioned means to said chute.

9. In a nail stripper, a box, a cover hinged thereon, an inclined hopper attached to said cover, a nail chute secured to said hopper, nail tracks on said chute for positioning the nails with their heads upward, nail guides extending from said chute, said nail tracks being adapted to project between said nail guides to insure the delivery of the nails to said guides, means for adjusting the width of said nail tracks, means for adjusting the width of said nail guides, side bars connecting said last mentioned means with said chute, arms for supporting said nail guides, means on said arms for adjusting the height of said nail guides, and a standard for adjusting the height of said hopper and said chute, said standard and one of said arms being offset to permit said nail stripper to be collapsed and housed in said box.

HERBERT C. HAMER.
